UNITED STATES PATENT OFFICE.

REUBIN HOWARD, OF PARKDALE, OREGON.

MUSICAL INSTRUMENT.

Application filed August 1, 1924. Serial No. 729,545.

This invention relates to musical instruments and more particularly to stringed instruments.

The object of the invention is to provide 5 an instrument of the banjo type practically combining three instruments in one constructed so as to have the richness and lasting tone of the guitar, the volume and sound of a piano, and which may be made to sound 10 like a banjo or mandolin.

Another object is to construct an instrument of this character to resist dampness and to adapt it to be readily cleaned.

Another object is to provide an instrument 15 of this character having a plurality of sound apertures accurately sized and arranged to insure richness of tone.

With the foregoing and other objects in view which will appear as the description 20 proceeds, the invention resides in the combination and arrangement of parts and in the details of construction hereinafter described and claimed, it being understood that changes in the precise embodiment of 25 the invention herein disclosed may be made within the scope of what is claimed without departing from the spirit of the invention.

In the accompanying drawings:

Figure 1 represents a top plan view of the 30 instrument embodying this invention.

Fig. 2 is a side elevation thereof, and

Fig. 3 is an enlarged detail longitudinal section taken on the line 3—3 of Fig. 1.

Fig. 4 is a detail perspective of the bridge 35 and support used in connection therewith.

In the embodiment illustrated, the instrument constituting this invention is made in the form of a banjo comprising a calf skin head 1 varnished on both faces and a metal 40 rim 2 of a size smaller than the skin head and provided in the perimeter thereof with a plurality of vibration or sound openings 3 which are accurately sized and arranged to provide richness of tone. The head 1 and rim 2 are secured together by the ordinary clamps or brackets 4 such as are used 45 in instruments of this character particularly in the banjo and both are varnished which adapts them to resist dampness and provides for their being wiped off and kept clean.

A wooden ring 5 is arranged inside the rim 2 and a metal straining hoop 6 is arranged on the outside. A metal tail piece 7 secures the strings 10 at their rear ends and a 50 steel bridge 8 supports the strings in the usual manner (see Figs. 1 and 2). A sup-

port 20 is used in connection with bridge 8 and as shown in Fig. 4 has a short leg 21 and a long leg 22 equipped with flat feet 23 similar to the feet of the bridge 8. This 60 support extends under and supports the bridge 8, increases the sound and softens the tone and when the end having the long leg is placed under any harsh string it regulates it in unison with the others. 65

This instrument has five strings of a size larger than the regular banjo strings. The fifth string numbered 11 is of the same length as the fifth string on a banjo, the other four being shorter than the banjo 70 strings. The neck 9 of this instrument is shortened at the top and is equipped with the usual frets 12 arranged in longitudinally spaced relation on the outer or front face thereof, constituting the finger board of the 75 instrument. Arranged on the finger board at its junction with the tuning peg carrying outer portion 13 is a steel nut or rib 9* which supports the strings and prevents them from touching the finger board 80 and frets until they are pressed down by the fingers.

A plurality of characters are shown at 14 on the finger board and the portion 13 which are designed to indicate the positions for 85 playing. The fifth string 11 passes through an opening 15 in the neck near its outer end, which is equipped at this point with an eye. This string after passing through the neck or finger board and extending outwardly 90 underneath the finger board passes up through an opening at the outer end of the tuning peg head as shown at 16. It will be observed that this fifth string passes through the neck adjacent the third fret 12 and after 95 again passing to the upper face of the peg head is wound around a screw 17 which is actuated by a tuning peg 18. The other strings are equipped in the same manner with pegs shown at 19. 100

The strings of this instrument may be so tuned as to adapt it to be played as a banjo by either chords or note and when played in chords it has a wonderful rich lasting tone especially adapted as an accompaniment for 105 vocal music. When played like the banjo by note, the effect is that of the banjo. This instrument may also be tuned and played with a mandolin pick and has then the rich effect of the mandolin. 110

It will then be seen that this instrument practically embodies three instruments in

one, the standard size of the head being ten and one-half inches in diameter and the concert twelve inches.

I claim:—

- 5 In a stringed musical instrument, a head, strings stretched over the head, a bridge including end portions having inturned extremities resting on the head, a support for the bridge, said support having downwardly
- 10 extended end portions formed with inturned extremities resting on the head, one of the

downwardly extended end portions of the support being shorter than the opposite end portion thereof, so that the upper part of the support will be inclined, said support 15 engaging under the bridge to tighten the strings and insure a solid bridge, and change the tone of the instrument.

In testimony that I claim the foregoing as my own, I have hereto affixed my signature. 20

REUBIN HOWARD.
